(57) **CLAIM**

We claim an ornamental design for a transcranial magnetic stimulation system, as shown, and described.

DESCRIPTION

The subject matter disclosed and claimed herein is related to the subject matter disclosed and claimed in U.S. patent application Ser. No. 29/283,157 filed on even date herewith.

FIG. 1 is a right perspective view of a transcranial magnetic stimulation system in accordance with the design;

FIG. 2 is a left perspective view of the transcranial magnetic stimulation system of the design that is depicted in FIG. 1;

FIG. 3 is a right side view of the transcranial magnetic stimulation system of the design that is depicted in FIGS. 1–2;

FIG. 4 is a left side view of the transcranial magnetic stimulation system of the design that is depicted in FIGS. 1–3;

FIG. 5 is a top view of the transcranial magnetic stimulation system of the design that is depicted in FIGS. 1–4; and,

FIG. 6 is a front view of the transcranial magnetic stimulation system of the design that is depicted in FIGS. 1–5.

The dashed lines are shown in the views for illustrative purposes only and form no part of the claimed design.
